UNITED STATES PATENT OFFICE

CHARLES S. CRAWFORD, OF DETROIT, MICHIGAN, ASSIGNOR TO GENERAL MOTORS CORPORATION, OF DETROIT, MICHIGAN, A CORPORATION OF DELAWARE

RUNNING BOARD SUPPORT

Application filed May 8, 1929. Serial No. 361,385.

This invention relates to running boards and has particular reference to a means for securing the running board to the ordinary running board support on an automotive vehicle.

In running board constructions of today, the underside of the board usually has secured thereto a plurality of channel members to hold the board together. The channel faces 10 toward the board and its base usually rests directly on the conventional running board supports secured to the chassis frame. In the past, some difficulty and annoyance has been experienced in attaching and detaching 15 the channel members to the supports due to the fact that it was extremely inconvenient to get to the inside of the channel member. The usual bolt which passed through the support and channel member was either inserted from 20 below through the support into the channel member or vice versa. Where the bolt was inserted from below it was found impractical to hold the nut inside the channel member, and where the bolt was first inserted through 25 the channel member and extended downwardly into the support, similar difficulty was experienced in holding the bolt so that a nut could be applied and it was also impractical to remove the bolt. It is an object of 30 the present invention to devise a fastening or securing means which will eliminate the objections of prior constructions and will enable the bolt to be inserted from below and render the nut easy of application.

The object of the invention is accomplished 35 by providing an opening in the side of the channel member opposite the place at which the bolt is to be inserted. The nut, instead of being the usual square or hexagonal one, is formed with an extension so that it is really 40 in the form of a bar having a threaded opening in its end. This bar is inserted through the opening where it may be held and the bolt screwed into place through the opening. When it is desired to remove the board, the bolt may be unscrewed and the bar withdrawn through the lateral opening.

On the drawings:

50 Figure 1 is a plan view of the chassis of an

automotive vehicle, showing the running board applied.

Figure 2 is a sectional, detailed view on the line 2—2 of Figure 1 and showing the invention in detail.

55 Figure 3 is a section on the line 3—3 of Figure 2.

Figure 4 is a detached plan view of the channel member and bar.

Referring to the drawings, the numeral 2 60 indicates the chassis of the automotive vehicle. To the chassis there are secured the usual running board supports 4, for receiving the running board 6. To the bottom of the running board, there are secured the channel members 8 provided with the lateral flanges 10 which abut against the bottom of the board and which flanges are the means through which the board and channel member are secured together. The flanges may 65 be welded or bolted to the board 6. Each support 4 is preferably of channel shape and has its end tapered as shown at 12 in Figures 2 and 3.

70 As is seen in Figures 1 to 3 inclusive, the channel members 8 are arranged at the bottom of the board 6 so that they will conform to the supports 4. Both the channel members 8 and supports 4 have the slots or openings 14 and 16 respectively which are for the purpose of accomplishing adjustment and receiving a securing bolt 20. The head of the bolt 20 is received in the channel of the support 4 and is inserted from below and upwardly into the channel of the channel member 8.

75 With prior constructions, some difficulty has been experienced in applying a nut to the threaded end 22 of the bolt 20, due to the fact that the bolt end is inclosed in the channel 80 and is accessible from the channel ends only. In the present invention, this difficulty is eliminated by providing openings 24 in the side of one of the legs of the U-shaped channel 8. These openings are placed opposite the opening 14 in the base of the channel and are for the purpose of receiving or permitting the insertion of a bar or elongated nut 26, one 85 end of which is provided with a threaded opening 28 and in which the threaded end 100

22 of the bolt is adapted to be received. The bar 26 is of a length sufficient to permit it to project from the side of the channel member 8 so that it may be grasped by the hand, 5 or a suitable tool applied to hold or remove the same. After the bolt has been started in the nut 26, the sides of the openings 24 will hold the nut.

In prior constructions the nut was usually 10 welded to the inside of the channel but in case the threads became stripped it was necessary to retap the nut or remove it entirely and weld a new one in place. The present invention eliminates the difficulties of the 15 former construction by making the nut removable and readily replaceable.

A washer 30 and lock washer 32 are interposed between the bolt head and the bottom 20 of the channel 4. When the bolt 20 is tightened it will cause the washer 30 to slightly bend or camber because of the fact that it straddles the slot 16 and the pressure is applied at the middle. This camber will prevent the washer from turning by causing the 25 washer to engage with the sides of the slot 16.

From an examination of Figure 2, it will be apparent that if it is desired to remove the running board 6, the bolts 20 may be 30 unscrewed by the application of a wrench or suitable tool to the bolt head. When the bolt has been unscrewed, the bar 26 may be laterally withdrawn. When all the bolts are 35 removed, the running board may, of course, be bodily withdrawn. The reapplication or securing of the running board in place is believed obvious from the description above given.

I claim:

1. In a securing means for two members, 40 one of which is channel shaped, said channel member having a lateral opening, a bolt passing through both members, and a bar passing through and extending without said opening, said bar having a threaded opening 45 adapted to be engaged by said bolt.

2. In a securing means for two members, one of which is of metal and U-shaped and is provided with an opening in one leg of the U, a bolt passing through both members, 50 and a bar extending through said opening and having a threaded opening adapted to be engaged by said bolt.

In testimony whereof I affix my signature.

CHARLES S. CRAWFORD.
